CLAIM

The ornamental design for combined solar lamp and video camera, as shown and described.

DESCRIPTION

FIG. 1 is a perspective view of combined solar lamp and video camera showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof;

FIG. 9 is a perspective view with the folded up supports viewed from another visual angle thereof;

FIG. 10 is a perspective view of the folded up combined solar lamp and video camera viewed from another visual angle; and,

FIG. 11 is a reference view of the combined solar lamp and video camera in a use state.

The broken line showing of the environment is for illustrative purposes only and forms no part of the claimed design.

1 Claim, 10 Drawing Sheets
